(57) **CLAIM**

The ornamental design for an expansion accessory for mobile device, as shown and described.

DESCRIPTION

FIG. 1 is a perspective view of an expansion accessory for mobile device showing a first embodiment of my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing the article mounted on a mobile device;

FIG. 10 is a perspective view of an expansion accessory for mobile device showing a second embodiment of my new design;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a perspective view thereof, showing the article mounted on a mobile device.

The broken lines showing the mobile device in FIGS. 9 and 18 depict environmental subject matter only and form no part of the claim. All other broken lines depict portions of the expansion accessory for mobile device that form no part of the claimed design.

1 Claim, 16 Drawing Sheets
